CONTROLLED LEAD PENCIL

Francis A. Wade, Point Pleasant, and William Metzner, Philadelphia, Pa.

Application September 23, 1952, Serial No. 311,076

5 Claims. (Cl. 120—21)

1

The present invention relates to stationery and more particularly to a lead or crayon pencil intended primarily for use by classes of children in school.

In pencils of the type wherein the lead is manually fed to writing position the mechanisms and assemblies have been made of many parts, more or less complicated, costly, and open to the objection of being readily taken apart so that parts are lost or incorrectly re-assembled. This objection applies particularly to school children whose curiosity prompts them to investigate the workings of such pencils. Where the school furnishes such pencils the loss and replacement becomes an economy problem.

Some of the objects of the present invention are to provide an improved lead or crayon feeding pencil; to provide such a pencil having a minimum of parts; to provide a pencil feeding construction in which the parts are sealed and inaccessible to prying investigators but which can be taken apart by the teacher for part replacement; to provide a pencil which is simple in construction and operation and wherein the lead can be accurately controlled for feeding; to provide a pencil in which the lead is manually fed and includes as a part thereof a measuring means by which a point of selected length can be readily protruded for use; to provide a pencil of so simple a design that it can be manufactured and sold at a price to compete with wooden pencils presently in almost universal use in school; to provide a pencil that may be sharpened with a rod or wire more easily and with less waste than sharpening wooden pencils with a mechanical pencil sharpener as is the present custom in schools; to provide a low cost pencil for school use that will be uniform in length, a feature most desirable in teaching handwriting; to provide a holder that the pupils at their desks will have difficulty in taking apart but that teacher, by the use of heat or water, can readily take apart for cleaning or for replacing the washers; and to provide other objects and improvements as will appear hereinafter.

In the accompanying drawings Fig. 1 represents a longitudinal median section of a pencil embodying one form of the present invention; Fig. 2 represents a perspective of a feeding rod used with the pencil; Fig. 3 represents a fragmental section of the point end of the pencil showing the position of the parts under feeding action of the rod; Fig. 4 represents the same section showing the position of the parts when relieved of the rod pressure with the lead in writing

position; Fig. 5 represents a section on line 5—5 of Fig. 1; Fig. 6 represents a side elevation of the pencil partly broken away, showing the feeding rod as initially grasped by a hand; and Fig. 7 represents a view of Fig. 6 showing the position of the hand at the end of a feeding operation.

Referring to the drawings, one form of the present invention comprises a barrel 10 preferably cylindrical, and formed of plastic or other material, having an axially disposed bore 11 for the passage of the writing lead 12. The bore 11 is dimensioned to permit free relative axial movement of the lead without either binding or too loose movement of the lead. In other words, it forms a smooth guide to keep the lead centered as it is fed axially therealong. One end of the barrel 10 is reduced in diameter for telescopic assembly with a truncated point piece 13, for assembly by uniting the parts together by heat, soluble adhesive or other suitable means to produce a pencil incapable of being taken apart by a pupil but permitting a teacher to do so for replacement of parts. The point piece 13 has a bore 14 axially aligned with the bore 11 but opening at its inner end into a control chamber 15. This chamber 15 is defined at one side by the barrel end 16, which may be a plane face but is preferably slightly convex, and at the opposite side by a shoulder 17 and tapered wall 18 of the piece 13. The spacing between the end 16 of the barrel 10 and the shoulder 17 is such as to receive a control washer 19 through which the lead passes to be controlled thereby, the periphery of the washer seating in the barrel. In the preferred construction, one side of the washer 19 abuts the shoulder 17, while the washer thickness leaves a slight clearance with respect to the convex end 16. The washer 19 is of live rubber or other satisfactory resilient material, and the diameter of its aperture is somewhat smaller than the lead diameter to give a gripping fit against the lead 12. This fit resists a relative movement of the lead inwardly of the point piece 13 under normal writing pressure and so maintains the lead properly projected for writing, because the washer then abuts the convex end 16. For relative movement in the direction to advance the lead to writing position, the washer automatically flexes to substantially cone shape and bends about the shoulder, thereby permitting the lead to be advanced through the washer by pressure at its rear end. From the foregoing it will be seen that the counter-bore of the point piece forms an annular shoulder opposed to the washer 19, which in conjunction with its spacing from

the lead, forms means to permit the washer to deform axially under an applied feeding pressure on the lead and thus relax the washer grip. Also the convex end of the barrel coacts with the washer as a means to maintain the desired gripping action under the writing pressure upon the lead.

In order to advance the lead for repointing, a push rod 20 is provided which is dimensioned to enter the bore 11 at the rear end to propel the lead through the washer as deformed until the desired length of protruding lead is obtained.

As a means of obtaining predetermined measured lengths of protruding lead, the end of the barrel 10, which receives the push rod 20, is scarfed to provide an abutment 21 at one side which merges as substantially an S curve into a clearance 22. The depth of the clearance 22 forms a selected measure of one lead-advancing operation to give, for example, a quarter inch feed if the clearance is so dimensioned. Thus, the user grasps the rod 20, inserts it into the barrel bore 11 into contact with the lead therein. The hand of the user now takes a position upon the rod 20, as shown in Fig. 6, with the thumb resting against the abutment 21, after which either the rod or the barrel can be rotated to bring the thumb into register with the clearance, whereupon the rod can be pushed inwardly until the thumb is stopped by the end of the clearance, as shown in Fig. 7. This inward feeding of the rod 20 is transmitted to the lead, which, by reason of the tight fit of the washer, due to the washer aperture having a diameter slightly less than that of the lead, and by the holding of the washer periphery against the barrel, causes the washer to deform outwardly about the abutting shoulder 17 and so reduce the gripping action as to permit the lead to move relative to the washer. When the measured length of lead has been protruded, the rod 20 is removed thereby leaving the lead under control of the washer. Therefore, since the outward pressure of the lead is removed, the elasticity of the washer and the release of its pressure against the shoulder causes it to snap back to its normal position with a restored gripping of the lead. This action shortens the protruding end of the lead by the restoring movement of the washer. Now in its restored position the washer abuts the convex end of the barrel and so resists inward movement of the lead under all usual writing pressure. However, a very heavy pressure upon the lead, greater than that used in writing, will result in the lead being forced back into the barrel in case it is desired either to shorten the point or withdraw the protruding lead to prevent breaking when the pencil is not in use.

Having thus described our invention, we claim:

1. A pencil comprising a barrel having a bore

for guiding a lead, a point piece having a barrel end receiving bore, a lead guiding bore alined therewith, and an intermediate bore terminating in an annular shoulder spaced from the juxtaposed end of said barrel to form a chamber, means interconnecting said barrel and point piece, and a resilient washer disposed transversely of said chamber to elastically grip the portion of the lead in said chamber, said washer being dimensioned to abut said shoulder under feeding movement of the lead, and to abut said barrel end under reverse movement of the lead, whereby under lead feeding pressure said shoulder fulcrums said washer to deform it axially to relax said grip and permit the lead to move axially, while under writing pressure said barrel end causes said washer to maintain said grip.

2. A pencil in accordance with claim 1, wherein said intermediate bore is outwardly flared towards said chamber.

3. A pencil in accordance with claim 1, wherein the chamber end of the barrel is convex.

4. A pencil in accordance with claim 1, wherein the lead feeding means is a hand operated push rod insertable in the barrel bore and a scarfed end on said barrel has a length as a measure of lead feeding, said end forming two hand limit positions, one defining an initial position of the hand grasping said rod, and the other defining the end of the hand movement pushing the rod.

5. A pencil comprising a barrel having a bore for guiding a lead, a point piece having a bore as a continuation of said barrel bore, said piece having a barrel receiving counter-bore terminating in an annular shoulder juxtaposed to the end of said barrel and forming a clearance about said lead, and an elastic washer disposed between said shoulder and said barrel having a through hole to grip said lead, whereby pressure feeding of the lead deforms the washer axially about said shoulder into said clearance to relax the washer grip while reverse writing pressure restores said washer to gripping position abutting the end of the barrel.
